UNITED STATES PATENT OFFICE

ARTHUR THOMAS, OF THORNTON HEATH, ENGLAND, ASSIGNOR TO THE ACCOUNTING & TABULATING CORPORATION OF GT. BRITAIN, LIMITED, OF LONDON, ENGLAND

CALCULATING DEVICE

Application filed March 15, 1928. Serial No. 261,885.

The invention relates to adding machines and particularly to that type in which by a suitable fitting or attachment, subtraction is effected by adding the complement of the 5 subtrahend.

The present invention is particularly applicable though not restricted to the type of machine in which holes are punched in a series of cards to denote the numbers to be 10 added. In such a machine, one advantage that may be secured by use of a subtraction attachment of the kind to which this invention relates is that by a mere reversal of the particular card, the number punched there- 15 on is subtracted instead of added.

Thus, taking the two series of numbers, 0 to 9:—

0	1	2	3	4	5	6	7	8	9
9	8	7	6	5	4	3	2	1	0

20 the second set being reversed in respect to the first set, it will be seen that the sum of opposite numbers amounts to 9 in each case; consequently, so long as the numbers are 25 symmetrically spaced and the 0's and 9's coincide when the card is reversed, the passage of the reversed card through the machine will cause the complement of the subtrahend to be added, i. e., the difference between 30 the subtrahend and another number having as digits as many 9's as there are digits in the subtrahend.

If it is wished, for example, to subtract 21 35 from 56, the latter number being already accumulated in the adding mechanism, the card, according to the system of operating in question, is reversed and its complement 78 (apart from the corrections to be explained) is then added, giving 134 as the sum.

40 It will be seen, however, that as the result sought is 35, in order to secure the true result, it becomes necessary (a) to add a unit and (b) to eliminate the digit 1 on the left, this requirement being effected by adding as 45 many 9's within the capacity of the machine as lie to the left of the complement.

Thus, Figure 1 shows a card, A, having 50 perforations, *a*, *b*, to denote the number, 21, to be subtracted and having also a special perforation, *c*, the function of which is to

cause the subtraction attachment hereinafter described to be operated when the card is reversed as shown in Figure 2. In this latter position, the perforations, *a*, *b*, denote the number 78, which would be accordingly 55 added by the adding mechanism in the normal manner apart from the fact that, due to the perforation, *c*, the subtraction attachment comes into operation to effect the corrections indicated above. 60

The present invention in its complete form is adapted to perform both the functions (a) and (b) but I wish it to be understood that the combinations of parts claimed or some of them are applicable to systems of subtracting by adding the complement other than that specifically referred to above, which is described in order to illustrate the principle on which the invention is based. Thus, 65 according to another method, the card is not reversed but wires are led from the 2 and 1 perforations to operate the 7 and 8 stops. 70

In order that the present invention may be clearly understood, reference is made here- 75 with to the accompanying diagrammatic drawings illustrative of one specific form of the invention by way of example:—

Figure 3 shows an end elevation of sufficient of the adding head of an adding and printing machine to enable the present invention to be understood; 80

Figure 4 shows a corresponding rear elevation;

Figure 5 shows a perspective view of the 85 slide operating the unit-sector stop and the "0" shutter-operating comb;

Figure 6 is a front perspective view of the controlling mechanism,

Figure 6* being a corresponding rear view; 90

Figure 7 shows in plan the movable stop in its subtraction position in relation to the unit sector and shows also the means for actuating the "0" shutter-operating comb;

Figure 8 shows the movable stop in its 95 normal position in relation to the unit sector;

Figure 9 shows the mechanism with the slider restored;

Figure 10 shows the slider restored and 100 latched;

Figure 11 shows the released slider after making its operative stroke;

Figure 12 shows a view of a "0" shutter removed from the rest of the mechanism,

Figures 13 and 14 being sections of the "0" shutter on the lines 13-13 and 14-14 respectively of Figure 12, the shutter in each case being shown in conjunction with a stop, while finally

Figure 15 shows a view a "0"-shutter-operating comb likewise removed from the mechanism.

In carrying the invention into effect according to the form shown, the adding mechanism comprises the usual features well-known to experts in this art and described for example in the typical machine shown in British Patent, No. 26,896 of 1913.

The main parts shown comprise a frame, B, having in particular a rear bar, 2, a connecting box, C, provided with pins, 4, and a sensing-pin box, D, which is raised and lowered periodically by the cam, 1, mounted on the rotating shaft, 3. The operation of the connecting-box pins, 4, is controlled in the usual manner from perforated cards fed into place between the sensing-pin box and the connecting box by rollers, E, E', and withdrawn by rollers, F, F', the pins, 4, serving in a well-known manner to raise the stops, 5, so as to determine how far a particular sector advances on its outward movement before a heel, 6, butts against the corresponding stop. For the purpose of the following description the typical sector, 7, shown in Figure 3, may be taken as the unit sector.

As explained above, in order to subtract by adding the complement, it is necessary to add a unit while in addition 9's must be added to 40 the capacity of the machine in all rows to the left of the complement of the subtrahend. These operations are effected by the following mechanisms:—

A shaft, 8, is rotatably mounted in brackets, 9, attached to the frame bar, 2, this shaft carrying a plurality of levers, 10, spaced along its length to correspond with the adding units, two of which are shown in Figure 4; a lever, 11, fixed to the shaft, 8, at one end is 45 connected by a link, 12, having a slot, 13, to a lever, 14, secured to the main operating shaft, 15, the lever, 14, being provided with a pin, 16, engaging with the slot, 13, while the link, 12, is associated with a spring, 12^a, tending 50 to move it to the left in Figure 3.

As the subtraction attachments are similar, for simplicity only one will be described. The attachment comprises a bracket, 17, consisting of a vertical plate, 18, having a bent-over horizontal portion, 18^a, at the top and a bent-over horizontal portion, 18^b, at the bottom (see Figure 4) this plate being secured to a block, 19, provided by help of the loose side plate, 20, (with pinching screw, 21) with a dovetail groove, 22, on its upper face (see

Figure 5) so that the block, 19, may engage with and be clamped to a corresponding part of the frame bar, 2. An individual subtraction attachment can thus, if desired, be positioned to correspond with any individual adding unit.

On the top bent-over portion, 18^a, of the bracket, 17, a bell-crank, 23, is mounted capable of turning about a vertical axis, this bell-crank (see particularly Figures 7 and 8) having one arm provided with two stops, 23^a and 23^b, while the other arm has a turned-down portion, 24, (see Figures 5 and 8) provided with a horizontal pin, 25. Similarly, on the lower bent-over portion, 18^b, of the bracket, 17, a second bell crank, 26, is pivoted to turn about a vertical axis having one arm, 27, to which a spring, 28, is secured and a second arm, 29, having a turned-down portion, 30, (see Figures 9 and 11) adapted to engage with a pin, 31, on the "0" shutter-operating comb, 32, (see Figure 7) the nature and function of which are explained in detail below.

To operate these bell cranks, a slider, 33, is provided having slots, 34, 35, engaging with pins, 36, 37, secured to the plate bracket, 17. This slider in addition has an upwardly-projecting lug, 38, adapted to engage with the pin, 25, of the upper bell-crank, 23, and having also a downwardly-projecting lug, 39, adapted to engage with the arm, 27, of the lower bell-crank, 26. The slider is likewise provided with a pin, 40, by which it is moved to the restored position in a manner to be hereinafter described, and with a pin, 41, secured by a spring, 42, to an elongation of the pin, 37, this spring under stress tending to move the slider to the right as seen in Figure 5.

Finally, to the plate, 17, a manually-operable latch, 43, is pivotally secured at the point, 44, this latch having a toe, 45, adapted to butt against a corresponding heel, 46, on the slider, 33. The latch, 43, is also provided with a pin, 43^a, to which one end of the spring, 28, is secured.

For the common control of the plurality of subtraction units the following mechanism is provided:—

A lever, 47, is secured on the shaft, 8, at an angle substantially 180° from the end lever, 11. With this lever, two latches, 48, 49, (see Figure 6) are adapted to engage, the latches being pivoted to a block, 50, provided with a dovetail groove, 51, and pinching screw, 50^a, by which it is secured to the frame bar, 2, in any desired position. Both latches, 48, 49, are pivoted at the same point, 52, to the block, 50, but whereas the one, 48, is single-handed, the other, 49, is double-ended. The latch, 48, is connected near its latching end by the link, 53, having a slot, 54, to the pin, 55, of the lever, 56, pivoted at 57 to some suitable part of the frame or rigid attachment thereto, and having a

part, 58, as shown in Figure 6, lying in the path of a special subtraction wire, 59, (see Figure 3). A spring, 60^a, arranged as shown serves to raise the latch, 48. On the other hand, the end of the double lever, 49, remote from its latching end is connected by the link, 60, having a slot, 61, to the pin, 62, of a lever, 63, likewise pivoted to the frame at 57, and having an end portion, 64, in the path of another special wire, 65, which serves in a manner explained hereinafter to prevent operation of the subtraction attachment when no card is in the machine and the sensing pin-box rises.

In the type of machine described in which the swinging sectors are arrested by one or other of a series of stops, 5, it is necessary to provide for the particular case when none of the stops, 5, is lifted, as without such provision the sectors, 7, would swing forward and record the highest possible figure. To overcome this difficulty it is customary to provide what is known as a "0" shutter for each row of stops, the purpose of this shutter being to hold the sector in the zero position when no stop is lifted. Each shutter takes the form of a steel plate, 66, (see Figures 12 to 14) provided with pivots, 67, 68, to turn in the side plates, 69, 70. That part, 66^a, of the shutter, 66, to the right as seen in Figure 12, is flat, (see also Figure 13) and is provided with a projection, 66^b, adapted to engage with the heel, 6, of the adding sectors and is provided also with a tail, 66^c. The left-hand part of the shutter, as seen in Figure 14, is provided with a curved portion, 66^d, all the stops, 5, with the exception of the "0" stop being provided with a hump, 71. The end, 66^e, of the shutter lies against the "0" stop in the manner shown in Figure 13 when no stop is lifted, the projection, 66^b, on the shutter, thus being in a position to engage the heel, 6, of the relative adding sector. If the "0" stop is lifted, it pushes the shutter away and rises into a position beside it so that in that case both the zero shutter and the zero stop hold the sector in the zero position. If any of the remaining stops are lifted, the hump, 71, opens the shutter and thus allows the sector concerned to go forward till arrested by the particular stop in question.

As seen in Figure 4, a series of springs, 72, one for each shutter, are arranged to hold the shutters normally against their respective rows of stops.

If, however, a total is to be taken, it is necessary for the sectors to swing forward without being interfered with by the stops, the stroke of the sectors being governed by the accumulator wheels in a well-known manner. If the shutters are closed the sectors will all be held by the projections, 66^b, of the individual shutters and no total can be recorded.

To operate the shutters, therefore, when taking a total, a shutter-operating comb, 32, (see Figure 15) is provided which is mounted to slide on the side plate, 70, (see Figures 3 and 4) and is held to the right by a spring, 73, as seen in Figure 4. The upper edge of the shutter is provided with a number of teeth, 74, engaging respectively with the tails, 66^c, on the shutters. The comb, 32, carries a pin, 75, and with this engages a cam, 76, mounted on a spindle, 77, carried in bearings in the frame of the machine and operated by a lever, 78, connected by a link, 79, to a lever, 80, on the total-taking shaft, 81. When, therefore, a total is to be taken, the comb, 32, is moved by means of the cam, 76, to the left as seen in Figure 4, thereby opening all the shutters so that the sectors are free to move as determined by the accumulator wheels. This comb, 32, by the provision of a pin 31, operated by the bent-over portion, 30, of the bell crank, 26, is made use of according to the present invention for opening the shutter and thus allowing all those sectors to the left of the complement of the subtrahend to swing out to their full extent and thus add the series of nines required, as explained in the earlier part of this specification.

The operation of the form of the invention described is as follows:—

Assuming the parts of the subtraction attachment are in the restored position as shown in Figure 9, and a reversed subtraction card has been fed to the sensing position, the sensing pin-box rises in the usual manner and the special subtraction pin, 59, contacts with the end, 58, of the lever, 56, raising it and thereby pulling down the link, 53, and causing the latch, 48, to release the lever, 10. The spring, 12^a, will then move the lever, 11, to the left as seen in Figure 3 and the lever, 10, to the right. Removal of this latter lever permits the spring, 42, to operate the slider, 33, the manually-operable stop, 43, being assumed in its inoperative position as shown in Figure 9.

As the slider, 33, moves to the right as seen in Figure 9, the lower lug, 39, is removed from the arm, 27, of the bell-crank 115 26, thereby causing the bent-down portion, 30, of its arm, 29, to operate the "0" shutter-operating comb, 32, by way of the pin, 31, this action being necessary to the proper performance of the adding mechanism's function before the unit stop is moved. As the slider, 33, continues its movement to the right, the upper lug, 38, comes into contact with the pin, 25, of the bell-crank, 23, thereby moving the latter from the position shown in Figure 8, where the unit sector, 7, butts against the stop, 23^a, in normal adding, to the position shown in Figure 7, with the second stop, 23^b, in a position to engage the unit sector, 7. The consequence of this move- 120 125 130

ment is that when the adding sectors run back, the unit sector travels an extra distance sufficient to cause the addition of one unit to the total.

On each stroke of the machine, the lever, 14, moves to the right and by way of the link, 12, lever, 11, shaft, 8, and lever or levers, 10, returns the slider or sliders to the position shown in Figure 9, where the parts are locked by the latch lever, 48, engaging with the lever, 47.

In order to prevent operation of the subtraction attachment, e. g., in a power-driven machine, when no card is present, a special wire, 65, is provided corresponding to a position on the card which is never perforated. In the case, therefore, when no card is in the machine, and only in that case, the wire, 65, rises and lifts the end of the lever, 63, drawing down the link, 60, and so raising the latched end of the lever, 49, which engages with the lever, 47, and prevents the subtraction attachment functioning.

It will thus be seen that the subtraction attachment can function only if the subtraction wire, 59, alone rises. If both wires, 59 and 65, are down the lever, 47, is latched, and similarly if both wires are up the lever, 47, is latched.

A single mechanism may thus control any number of subtraction attachments.

It will be obvious to those skilled in the art that the invention is applicable to other forms of adding machine than that shown and described while in addition many departures can be made from the particular mechanism described, and I therefore desire the appendant claims to be read as broadly as the law permits.

Having now described my invention, what I claim as new and desire to secure by Letters Patent is:—

1. In combination in a calculating machine, a plurality of adding units, each unit comprising racks and operating mechanism in respect to a plurality of denominations, a subtraction attachment and means for positioning said attachment in operative relation to any one of said units.

2. In combination in an adding mechanism, a plurality of adding units, a subtraction attachment for each of said units, means for storing energy in each of said attachments and means common to all said units for actuating said energy-storing means.

3. In combination in an adding mechanism, a plurality of adding units, a subtraction attachment for each of said units, means for storing energy for operating said attachments, and means common to said attachments for preventing release of said stored energy during a normal adding operation.

4. In combination in an adding mechanism, a plurality of adding units, a subtraction attachment for each of said units, and

common mechanism for controlling the operation of said subtraction attachments.

5. In combination in an adding mechanism operated by perforated cards, a subtraction attachment and means for preventing operation of said attachment when no card is present.

6. In combination in an adding mechanism operated by perforated cards, a subtraction attachment, means operated from a special subtraction perforation in said card for rendering said subtraction attachment operative and means acting reversely to said rendering means for preventing operation of said attachment when no card is present.

7. In combination, an adding mechanism comprising a series of adding elements, one for units, one for tens and so on to the capacity of the mechanism, a subtraction attachment associated therewith operating by addition of the complement of the subtrahend, said attachment including a two-position stop co-operating with said adding element for units, one position for normal adding and the other position for subtraction, said other position being such as to position said adding element to add an additional unit, together with automatic means for moving said stop from its normal adding to its subtraction position.

8. In combination, an adding mechanism, a subtraction attachment associated therewith operating by addition of the complement of the subtrahend, said attachment including means for storing energy for modifying the action of said adding mechanism to add a unit, together with means for preventing release of said stored energy during a normal adding operation.

9. In combination, an adding mechanism operated by perforated cards, a subtraction attachment associated therewith operating by addition of the complement of the subtrahend, said attachment including means for modifying the action of said adding mechanism to add a unit and including also means for adding as many 9's within the capacity of the mechanism as lie to the left of said complement and including also a single instrumentality responsive to a card perforation for actuating both said modifying means and said adding means, together with means for rendering said actuating instrumentality inoperative at will.

10. In combination, an adding mechanism, a subtraction attachment associated therewith operating by addition of the complement of the subtrahend, said attachment including means for storing energy for modifying the action of said adding mechanism to add a unit and for storing energy for adding as many 9's within the capacity of the mechanism as lie to the left of said complement together with means for preventing release

of said stored energy during a normal adding operation.

11. The combination claimed in claim 10, in which the means for storing energy is common to both said modifying and said adding means.

In testimony whereof I have signed my name to this specification.

ARTHUR THOMAS.
